UNITED STATES PATENT OFFICE.

CHARLES S. BATDORF, OF BROOKLYN, NEW YORK.

MANUAL START AND STOP MOTION.

1,107,878.

Specification of Letters Patent. Patented Aug. 18, 1914.

Application filed December 11, 1909. Serial No. 532,542.

To all whom it may concern:

Be it known that I, CHARLES S. BATDORF, a citizen of the United States, residing at Brooklyn, county of Kings, State of New York, have invented certain new and useful Improvements in Manual Start and Stop Motions, of which the following is a full, clear, and exact description.

My invention relates to manual start and stop mechanism for machines, and is particularly concerned with mechanism of this character which is adapted for use in combination with machines for handling a plurality of articles, such, for example, as the coin stacking and wrapping machine illustrated in my Patent No. 998,830, July 25, 1911. It is to be understood, however, that the mechanism may be employed generally in conjunction with machines which are constructed to operate intermittently upon the passage of a coin or other article from a feed chute, or other conducting means, into the machine.

The object of the invention is to provide means for connecting the power shaft with the operative parts of the machine after the last article to be operated upon has passed from the feeding means into the machine, in order to enable the machine to perform its usual functions upon the last group or stack of articles so fed when the intermittent connection usually effected by the passage of the articles into the machine is interrupted, or has ceased.

The invention therefore contemplates broadly means for manually effecting the connection above described and the combination of such means with the means for effecting intermittent connection of the power shaft with the operative parts of the machine.

With these objects in view, the invention consists in the construction and arrangement of parts, one embodiment of which is illustrated in the accompanying drawings.

Figure 1 is a plan view of so much of the power mechanism of the machine illustrated in my co-pending application above referred to as is necessary to illustrate the present invention and showing my invention in conjunction therewith. Fig. 2 is a side elevation of so much of the coin advancing mechanism of said prior application as is necessary to illustrate the present invention in conjunction therewith. Fig. 3 is a plan view of the main features of the manual

start and stop mechanism. Fig. 4 is a side elevation of the parts shown in Fig. 3 and illustrated in conjunction with other operative parts of the construction. Fig. 5 is a detail view of the clutch mechanism to be used with my present invention. Fig. 6 is a side elevation of parts shown in Fig. 5, and, Fig. 7 is a horizontal sectional view of the parts shown in Fig. 5.

In the embodiment of my invention herein selected for illustration the same comprises a power shaft 1 journaled in a bearing 2 on a part 3 of the machine frame, said shaft carrying a pulley wheel 4 for connection with a suitable source of power. Also journaled in the machine frame is a shaft 5 carrying a worm gear 6 which is arranged to mesh with the worm gear 7, Figs. 5 and 7, which in turn is connected with the power shaft 1 by clutch mechanism hereinafter to be described.

Before entering upon a detailed description of the particular features in which the present invention resides, a brief description of the ordinary intermittent connection of the power shaft with the operating parts of the machine will be given with reference to the type of machine illustrated in my co-pending application above referred to. It is to be understood, however, that reference to said machine is made for illustrative purposes only and that the present invention may be employed in conjunction with machines of other types.

In Fig. 2 is illustrated a coin advancing mechanism similar in its general construction to that illustrated in my co-pending application and comprising a standard 8 upon which is mounted an adjustable feed chute 9, by which the coins are directed into the path of the several advancing elements. These elements comprise the presser 10, by which the coin is advanced from the feed chute into the path of the push bar 11, by which it is then advanced beneath the lift bar 12 to the coin stacking means, as fully described in the aforesaid application. The advance of each coin beneath the lift bar 12 raises the same and this movement is transmitted by connecting rod 13 and crank arm 14 to a clutch operating shaft 15 extending transversely of the machine. Upon the opposite end of the clutch shaft 15 is a depending crank arm (not shown) to which is connected a horizontal sliding clutch-operating push bar 16, which in turn is joint-

ed at 17 to a clutch operating member 18, slidably mounted in a casing 19 secured to the machine frame 3 and through which the power shaft 1 passes.

Referring particularly to Figs. 5, 6, and 7, the power shaft 1 has fixed thereto a collar 20 having a single tooth 21, and upon this collar is loosely mounted the spiral gear 7, said gear having a recess 22 in which is pivotally mounted a pawl or clutch lever 23, adapted to engage and disengage the single tooth 21, as will be presently explained. Adjacent to the worm gear 7, the casing 19 has an annular channel 24, said channel being adapted to receive a pin 25 projecting from the swinging pawl or clutch lever 23. The push bar 18 is actuated through the lift bar 12 and clutch shaft 15 each time a coin passes beneath said bar 12, by which said push bar 18 is reciprocated transversely of the channel 24 in the casing 19. The inner end of the push bar 18 is recessed at 26 to provide a lug 27 having an inclined wall 28. When no coin or other article is passing beneath the lift bar 12, the push bar 18 is retracted and the inclined wall 28 is withdrawn from register with the annular channel 24 in the casing 19 and is in engagement with the pin 25 on the swinging pawl 23 and holds said pawl out of range of action of the single tooth 21 of the fixed collar 20, thereby disconnecting the spiral gear 7 from the power shaft, but as each coin or other article passes beneath the lift bar 12, the push bar 18 is advanced and the inclined wall of the lug 27 is moved into register with the annular channel 24 and the pawl 23 is swung inward into engagement with the single tooth 21 of the collar 20. At the same time the pin 25 of said pawl enters the annular groove 24, whereby the spiral gear 7 is connected to the power shaft 1 and revolves with said shaft, the purpose being to have this gear make one complete revolution each time a coin or other article is advanced beneath the lift bar 12 and to come to rest again before the next coin or article is advanced. Immediately after the passage of the coin or other article beneath the lift bar 12, the latter drops, thereby rocking the clutch shaft 15 and withdrawing the clutch push bar 18 to the retracted position shown in Fig. 5, whereby as the spiral gear 7 completes its cycle the pin 25 strikes the inclined wall 28 of the lug 27 and the swinging pawl is withdrawn from engagement with the single tooth 21 of the sleeve 20, thus disconnecting the spiral gear from the power shaft. In actual operation, and when the machine is running at high speed, and coins or other articles are being continuously fed, the make and break of this clutch connection is hardly perceptible but whatever the speed of the machine the spiral gear is ordinarily not operated except by the actual passage of a coin beneath the bar 12.

Therefore, in the normal operation of the machine by feed of the coins or other articles the spiral gear is brought into operation only when a coin is being advanced and is allowed to make a complete rotation before 70 the advance of another coin.

The foregoing serves as an effective clutch mechanism for connecting the spiral gear and the power shaft while coins or other articles are passing beneath the lift bar 12 75 and being deposited in a stack holder ready for further operations of the machine. Any other well known clutch mechanism may be substituted for the foregoing device without departing from the spirit of the invention, it being understood that under ordinary conditions of operation of the advancing coins or articles that the clutch shall operate to connect the spiral gear with the power only when the coins or articles are 80 actually advanced beneath the lift bar 12, said gear remaining inoperative when the coins are not advanced, even though the advancing mechanism be in operation.

Having described the usual means for intermittently connecting the power shaft with the other operative parts of the machine, I will now describe the particular features in which the present invention resides.

When the last coin or article has passed beneath the lift bar 12, there is no longer any agent by which the intermittent connection of the power shaft with the operative parts of the machine can be effected. In order, however, to complete the cycle of operations 95 of the machine as a whole, upon the last stack of coins or articles which has been fed to the machine, it is necessary that the power shaft be again connected with the operative parts of the machine to perform such functions independently of this intermittent connection and to maintain such connection until the cycle of operations of the machine is completed. To this end I have devised a so-called manual start and stop mechanism 100 which may be thrown into operation after the passage of the last coin or article to the stacking or bunching mechanism, as described in my previous application.

Referring to Figs. 1, 3 and 4, 29 indicates 115 a cam shaft which is connected with and operated by the shaft 5 carrying the worm gear 6 in any desired manner, as shown, for example, in my application above referred to. This shaft 29 is designed to make one 120 complete revolution during one complete cycle of operation of the machine. I make use of this function therefore to maintain the clutch connection between the power shaft and the machine in operation for a corresponding period by the following means. On the shaft 29 is fixed a latch cam wheel 30 having an annular ledge 31, Fig. 3, on one face intersected by a radial beveled rib 32, Fig. 4, said latch wheel preferably hav- 125 130

ing an extended hub 33. Supported at one end upon the hub 33 is a forked latch bar 34, which is slidably mounted at its opposite end in a slot 35 in a transverse bar 36 of the machine frame and is normally held retracted by spring 34'. Pivoted upon the latch bar 34 is a spring latch 37, arranged to have its rear end held toward the latch cam wheel 30 by the spring 38. Said latch is provided with a shoulder 39 to engage the annular ledge 31 of said latch wheel. Said latch bar also is provided with a handle 40 for manual operation. The end of the latch bar 34 opposite the latch wheel is provided with a recess 41 arranged to receive a lug 42 fixed to the clutch shaft 15 and a stop pin 43 on the machine frame is interposed in the path of said latch bar.

In the normal intermittent operation of the machine as above described, the latch 37 is withdrawn from the latch wheel 30 and stands in retracted position, shown in Figs. 3 and 4. When, however, the last coin or article has passed beneath the lift bar 12, the latch bar 34 is pushed to the rear by the handle 40 until the latch shoulder 39 engages within the ledge 31 on said latch wheel. It is to be understood that the connection of the cam shaft 29 with the power shaft is so relatively arranged that upon the completion of a cycle of operations of the machine the beveled rib 32 of the latch wheel will stand in alignment with the latch 34. The inward push of the latch bar 34 through its engagement with the lug 42 rocks the clutch shaft 15 and throws the clutch into operative position, as herebefore described, whereby rotation of the latch cam wheel 30 is started. As soon as the beveled rib 32 passes in such rotation beyond the latch 37, the latter snaps into position within the ledge 31 and automatically maintains the clutch in operation, and inasmuch as the latch cam wheel completes a rotation simultaneously with the completion of a cycle of operations of the machine, the clutch will under ordinary conditions be maintained in operation for an equal period of time. Just as the cycle of operations of the machine is completed, however, the beveled rib 32 engages the latch 37 and releases the same whereupon the latch bar 34 is automatically retracted by the spring 34' and consequently the clutch is automatically thrown out of operation leaving the operative parts of the machine in position to begin a new cycle of operations.

Under ordinary conditions when the machine is operated intermittently by the feed of coins or articles, the operation of the machine may be interrupted, should such course become necessary upon accident to the machine or otherwise, merely by checking the feed. Likewise should conditions so demand, the operation of the machine

through the manual start mechanism just described may be interrupted by manually releasing the latch bar 37 against the spring 38, whereby the operation of the machine may be stopped at any point desired during its cycle.

While I have herein described a preferred embodiment of my invention and a particular construction of latch bar and connections thereof with the clutch mechanism, and have also described the invention in connection with a particular type of machine, it is to be understood that the invention may be varied in details and relative arrangement of parts and may be applied to machines of various types without departing from the spirit and scope thereof.

What I claim is:

1. In a machine the combination with a power shaft adapted to operate any desired mechanism of a second shaft, a clutch interposed between said shafts, a latch wheel on said second shaft, a latch connected with said clutch constructed and arranged to be moved into engagement with said latch wheel and having means to simultaneously throw said clutch into operative position said latch wheel having means to maintain such operative position during a predetermined period of operation of the machine. 95

2. In a machine the combination with a power shaft adapted to operate any desired mechanism of a second shaft, a clutch interposed between said shafts, a latch wheel on said second shaft, and a manually operable latch connected with said clutch constructed and arranged to be moved into engagement with said latch wheel and having means to simultaneously throw said clutch into engagement, such engagement and means on said latch wheel to maintain such engagement during a complete rotation of said latch wheel. 100

3. In a machine the combination with a power shaft adapted to operate any desired mechanism of a second shaft, a clutch interposed between said shafts, a latch wheel on said second shaft, a latch interposed between said clutch and said latch wheel, constructed and arranged to be moved into engagement with said latch wheel and having means to simultaneously move said clutch into operative position, said latch wheel having means to maintain said latch in engagement therewith during a complete revolution of said wheel and means to automatically disengage said latch therefrom at the completion of said revolution. 115

4. In a machine the combination with a power shaft adapted to operate any desired mechanism of a second shaft, a clutch interposed between said shafts, a latch wheel on said second shaft having an annular ledge and a rib adjacent said ledge, a latch connected with said clutch and constructed and 130

- arranged to be moved into engagement with said ledge and having means to simultaneously move such clutch into operative position said latch wheel having means to 5 maintain such operative position until said latch is disengaged by said rib.
5. In a machine the combination with a power shaft adapted to operate any desired mechanism a clutch interposed between said 10 shaft and mechanism, means for automatically throwing said clutch into and out of operation intermittently, and means for manually throwing said clutch into operation during a predetermined period of 15 operation of the machine.
6. In a machine the combination with a power shaft adapted to operate any desired mechanism the combination of a clutch interposed between said shaft and mechanism, 20 means for automatically throwing said clutch into and out of operation intermittently, and means for manually throwing said clutch into operation and for releasing the same.
- 25 7. In a machine the combination with a power shaft adapted to operate any desired mechanism the combination of a clutch interposed between said shaft and mechanism,

means for automatically throwing said clutch into and out of operation intermittently and manually operable means connected with said clutch adapted to be moved into engagement with said mechanism to simultaneously throw said clutch into operation, said mechanism having means to 30 maintain said operable means in engagement therewith during a complete cycle of operations of said mechanism and to automatically release said manually operable means.

40 8. In a machine the combination with a power shaft adapted to operate any desired mechanism of a second shaft, a clutch interposed between said shafts, a latch connected with said clutch and adapted to be moved into engagement with said latch wheel to throw said clutch into operative position, means to maintain such operative position during a predetermined period of operation of the 45 machine, and means for releasing said latch at will during such operation.

CHARLES S. BATDORF.
